(57) **CLAIM**

The ornamental design for a baseball bat holder attachable to a fence, as shown and described.

DESCRIPTION

FIG. 1 is a front and top perspective view of a baseball bat holder attachable to a fence, showing my new design, and shown in association with a fence, bats and hanging clips shown in broken outline and not a part of this invention; FIG. 2 is a top view thereof;

FIG. 3 is a front view thereof, the opposite rear view being plain and unornamented; and,

FIG. 4 is a sectional view thereof taken in the direction of the arrows upon the line 4—4 of FIG. 3.
